UNITED STATES PATENT OFFICE.

JAMES V. MOHLER, OF OELWEIN, IOWA, ASSIGNOR OF ONE-HALF TO EDWIN HARRISON HALL, OF OELWEIN, IOWA.

METAL CAR-ROOF.

1,356,649.

Specification of Letters Patent. Patented Oct. 26, 1920.

Application filed March 31, 1919. Serial No. 286,240.

To all whom it may concern:

Be it known that I, JAMES V. MOHLER, a citizen of the United States, and a resident of the city of Oelwein, county of Fayette, and State of Iowa, have invented certain new and useful Improvements in Metal Car-Roofs, of which the following is a specification.

My invention relates to improvements in metal car roofs and has for its object the production of a metal car roof which will be easily removable, durable in construction and economical in manufacture. A further object is the production of a metal car roof formed in sections and having a durable, economical, simple and water-proof method for joining the sections together. A further object is the production of a metal roof having an air chamber extending longitudinally thereof.

Other objects will appear hereinafter.

The invention consists in the combinations and arrangements of parts hereinafter described and claimed.

The invention will be best understood by reference to the accompanying drawings forming a part of this specification, and in which,

Figure 1, is a side elevation of a car embodying the invention,

Fig. 2, a fragmentary longitudinal section of Fig. 1,

Fig. 3, a transverse section of the device taken on lines 3—3 of Fig. 1,

Fig. 4, an end view of the device applied,

Fig. 5, a detail sectional view of a modified carline, and

Fig. 6, a fragmentary detail sectional view taken on lines 6—6 of Fig. 1.

The preferred form of construction, as illustrated in the drawings, consists of a car 1 having a metal roof 2, comprising an outside roof and an inner roof, leaving an air chamber between the two said roofs.

The inner roof is constructed of metallic sheets 3 secured at the ends by suitable fastening means 4 to the lower flange 5 of a channel iron 6, disposed transversely between sheets 3 and the outer roof sheet 7 adjacent the carline 8.

The outer roof sheet 7, which it is preferred to make of heavier material than the inner roof sheet 3, has an upwardly extending and inwardly bent flange 9 at both ends except at the ends of the car. This sheet 7

lies in close engagement, at its ends, to the upper flange 10 of the channel iron 6. The roof of the car is thus made up of a number of sections, as shown, the number of sections depending upon the length of the sheets 3 and 7 or the distance between the carlines 8. These sheets 3 and 7, or the distance between the carlines 8 can be of any desired predetermined length. It is thus seen that between the outer roof or the sheets 7, and the inner roof or the sheets 3, there is a longitudinally extending air chamber 17.

Extending transversely of the roof of the car, superimposed on members 7, at the section lines of sheets 3 and 7, is an inverted channel member 12 having downwardly projecting flanges 13 adapted to engage the ends of the members 9, thereby serving as a binding member to firmly lock the ends of the members 7 in their disposed position. The member 12 is bent to conform to the periphery of the roof of the car and thereby serves as a cap in making a water-tight joint at the sections of the roof.

The members 3 and 7 are curved so as to make a bow shaped roof. The sides of the members 3 and 7, and the ends of the members 12 are bent so as to be parallel to and in close engagement with the sides of the car with which used, as shown in Fig. 3. The sides of the members 3 and 7 and the ends of the members 12 are securely fastened to the side of the car by bolts 14 passing through the carline or longitudinally extending beam 16 and the member 18. Coöperating with the bolts 14, on the inside of the car, are nuts 15 closely clamping the members 3, 7 and 12 in position on the sides of the car. Extending longitudinally through the length of the car is a Z-shaped or doubled angled member 18 disposed with one end 20 between the members 3, 7 and 12 and the member 16, and the other end 19 projecting downwardly on the outside of the car, as shown in Fig. 3. The members 3, which are used as the terminal or end sections of the roof, are fastened at their inner ends, as already described.

At each end of the car, projecting up from the main body of the end of the car, and forming the lateral closure for the roof of the car, is a member 21, bent U-shaped at the upper end and having its lower end offset and downwardly bent so

as to form two sides of a **U**, as seen in Fig. 2, the **U**-shaped end of said member 21 being bent to conform to the periphery of the roof. Securely fastened, by suitable fastening means 22, on the inner surface and adjacent the upper edge of member 21, extending transversely of the roof, is an angle iron 23, to the horizontally extending web of which is securely fastened, by suitable fastening means 24, the outer end of terminal member 3. The outer end of terminal member 7 embraces the top or the base of the inverted **U** of member 21. The end of said member 7 is flanged downwardly and is securely fastened in close engagement with the short leg of the **U** part of member 21 by rivets 26, or other suitable fastening means.

Secured to the members 21 and 7, by rivets 26, is an angle iron 39 forming a bracket upon which is secured, by bolts 27 and nuts 28, the running boards 30 of the car, having a block 31 interposed between said bracket and said running boards. The bolts 27 are counter-sunk in said running boards, as clearly seen in Fig. 2, thereby affording a clear and uninterrupted surface on said running boards.

The carlines 8 are preferably constructed of metal, and are channel shaped and extend transversely of the car at the intersection lines or the ends of members 3 and 7. Bolts 32, having fixed collars 41, pass through the base 34 of the channel member 8, through the channel member 12 and into the block 40. Nuts 33, seated in grooves in said blocks 40, coöperate with said bolts 32 and serve to bind the members 8, 12 and 40 securely together. The base member 34 of member 8 is downwardly bent at its ends, forming downwardly projecting flanges 35, which are securely fastened by bolts 14, as shown in Figs. 3, 4 and 6.

Fig. 5 shows a modified form of construction of the carline 8'. In the modified form as shown in Fig. 5, the upper ends of the sides of the channel member 8' are outwardly inclined and securely fastened to the inwardly bent edges of members 7' by rivets 36, the ends of the members 3' being also upwardly flanged and secured to the sides of member 8', at its base, by rivets 38. In this modified form the member 8', as a whole, conforms to the shape of the periphery of the roof, whereas, in the form shown in Figs. 2, 3 and 6, only the upper edges of member 8 so conform. In the modified form used, the channel member 6 is also eliminated.

By the construction of a roof of the nature described, it is readily apparent that an air chamber, extending longitudinally of the car, is provided between an inner and an outer roof. As clearly seen in Figs. 2 and 5, the method of securing the ends of

the members 7 by an inverted channel iron affords an absolutely water-proof joint. The purpose of the air chamber in the roof of the car is to insulate the interior of the car from exterior temperature. It has been found, in loading a car with commodities such as wheat or grain, that the cargo is often-times of such a temperature when loaded as to materially raise the temperature of the interior of the car, and especially that of the air above the cargo. Under these conditions, where a single roof is used, it has been found, where the car suddenly enters an atmosphere of lower temperature, that the temperature inside of the car is lowered so quickly as to cause condensation and precipitation of the moisture in the air of the car. This results in moistening or dampening the grain and a consequent spoiling of part of the cargo. Especially is this the case when a car having a single roof, filled with grain, enters a tunnel where the atmosphere is damp and the temperature much lower than outside of the tunnel. With the insulated car roof, such as I have described, this objectionable feature is eliminated, as the car roof, being insulated by the air chamber, will retain the temperature within the car, or at least cause the change of temperature to be gradual, so that the temperature of the inside of the car gradually adjusts itself to the temperature outside of the car and thereby precipitation of the moisture is prevented.

The chamber between the two roofs, which serves as an insulating medium, may be packed with asbestos or some other non-conductor of heat, giving practically the same result as the air chamber.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

Having described my invention, what I claim as new and desire to secure by Letters Patent is:—

1. A metal car roof comprising metal members having upwardly projecting and inwardly bent flanges; metal members disposed under and spaced from said flanged members; and a channel iron interposed between said members adjacent their ends, substantially as described.

2. A metal car roof comprising metal members having upwardly projecting and inwardly bent flanges; metal members disposed under and spaced from said flanged members; a channel iron interposed between said members adjacent their ends;

and means for securing said members to said channel iron, substantially as described.

3. A metal car roof comprising a plurality of sections; metal members having upwardly projecting and inwardly bent flanges on the ends thereof; metal members disposed beneath and spaced apart from said flanged members; a channel iron interposed between said members adjacent their ends; and means for securing the sides of said members to the car with which used, substantially as described.

4. A car roof comprising a plurality of sections; a plurality of metal members having upwardly projecting and inwardly bent flanges; metal members disposed under and spaced apart from said flanged members; means for retaining said members in said spaced relation; and terminal metal members having an upwardly projecting and inwardly bent flange at one end, and a downwardly projecting flange at its opposite end, substantially as described.

5. In a car having carlines, a metal roof comprising metal members having upwardly projecting flanges interposed between said carlines; metal members disposed beneath said flanged members and spaced therefrom; a channel iron disposed between said members adjacent said rafters; and means for securing said members to said channel iron, substantially as described.

6. In a car having carlines, a metal roof comprising members having upwardly projecting and inwardly bent flanges at each end; metal members disposed beneath and spaced apart from said flanged members; means for retaining said members in said spaced relation, comprising a channel iron interposed between the ends of said members; means for connecting the ends of said members to said channel iron; and an inverted channel iron disposed transversely over the ends of said members and adapted to engage the inwardly turned flanges of said flanged members, thereby binding said members together, substantially as described.

7. A car roof comprising metallic members having upwardly projecting flanges on the ends; metal members disposed beneath and spaced apart from said flanged members; and a longitudinally extending member adjacent the lower edges of said members and being offset to engage the inner

surface of said members by one side, and to engage the outer surface of the car with which used by its opposite side, substantially as described.

8. In a metal car roof, members having upwardly projecting and inwardly bent flanges at each end; metallic members having an upwardly projecting and inwardly bent flange at one end, and a downwardly projecting flange at its opposite end; metal members disposed under and spaced from said flanged members so as to form an air chamber between said members; means for retaining said members in said spaced relation; an inverted channel iron disposed transversely of said members, at their ends, and adapted to engage said inwardly bent flanges; a downwardly projecting flange at each end of said channel iron; and means for securely clamping said downwardly projecting flange of said channel iron and the sides of said members to the sides of the car with which used, substantially as described.

9. In a metal car roof, members having upwardly projecting and inwardly bent flanges at each end; terminal metal members having an upwardly projecting and inwardly bent flange at the inner end thereof; a downwardly projecting flange at the outer end of said terminal member; metal members disposed beneath said flanged members and spaced therefrom; means for retaining said members in spaced relation; an upright end member formed U-shaped at its upper end; and means for securing the outer ends of said terminal members to said end member, substantially as described.

10. A sectional car roof comprising an insulating chamber extending longitudinally of said car; and hollow carlines disposed transversely of said chamber, substantially as described.

11. A sectional car roof comprising an insulating chamber extending longitudinally of said car; and hollow carlines disposed transversely of and traversing said chamber, substantially as described.

In testimony whereof I have signed my name to this specification in the presence of two subscribing witnesses.
